LINEMAN'S PROTECTIVE DEVICE

Hiram W. Johns, Union City, Ind.

Application January 3, 1939, Serial No. 249,099

1 Claim. (Cl. 174—5)

My invention relates to the improvements of protective insulating sleeves for encasing electrical conductors and insulators, designed and adapted to protect linemen and others from coming into contact with live wires.

The object of the invention is to provide a means by which the sleeves may be handled, spliced, or removed easily and with the least danger to the workers. This is obtained by the use 10 of eyes on insulating sleeves as shown by 8 in Figures 1, 2 and 3 and on insulator hoods as shown by 12 in Figures 4 and 5.

To effect the foregoing objects, the eyes are made of suitable resilient insulating material and 15 strong enough to withstand the pressure and usage when removing and handling. These eyes may be molded as the sleeves or hoods are made, vulcanized or attached by other methods.

An important object of the invention is to provide a means by which the sleeves and hoods may 20 be attached to the lineman's hoisting rope to raise or lower without danger of the sleeve or hood dropping. The eyes also make it possible to drag the sleeve from the pole to any desired 25 position in a span of wire.

Another object is to provide a means by which the sleeves and hoods may be removed from their position by hot sticks or ropes instead of climbing up through the structure.

30 In the accompanying drawing the eyes are fully illustrated, wherein like numerals refer to like parts throughout and in which—

Figure 1 is a side elevational view of a sleeve.
Figure 2 is an end elevational view of a sleeve.

Figure 3 is a transverse sectional view taken substantially on a line 3—3 of Figure 1.

Figure 4 is a side elevational view of an insulation hood. 5

Figure 5 is a transverse sectional view taken substantially on a line 5—5 of Figure 4.

Referring now to the drawing in detail, the invention covers the use of the eyes on the sleeve 10 and hood. The shape of the sleeve or hood may be made to any style as desired, to fit the wire or insulator. The eyes may be placed on the side diametrically opposite the split portions 6 and 10 or they may be placed on any other side. 15

It is believed the details of construction and manner of use of the device will be readily understood from the foregoing without further detailed explanation.

Having thus described the invention, what I 20 claim is:

A conductor sleeve comprising a longitudinally split tubular member of insulation material adapted for positioning on a conductor and an eye integrally formed with the member and projecting outwardly therefrom for attaching a hoist line thereto, said eye being adjacent an end of the sleeve and having its opening positioned transversely with respect to the member. 25
